[57] CLAIM

The ornamental design for a steam iron, as shown.

DESCRIPTION

FIG. 1 is a front perspective view of the steam iron of the present invention;

FIG. 2 is a rear perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top view thereof; and,

FIG. 8 is a bottom view thereof.

Applicants disclaim written indicia appearing in the figures as not constituting an integral part of the claimed design;
